US0D1054251S

(12) **United States Design Patent** (10) **Patent No.:** **US D1,054,251 S**
(45) **Date of Patent:** **** Dec. 17, 2024**

(54) **COMBINATION MUG AND BASE**

(71) Applicant: **GUANGDONG JIMI YOUPIN INTELLIGENT TECHNOLOGY CO., LTD.**, Guangdong Province (CN)

(72) Inventor: **Jiangang Ji**, Guangdong Province (CN)

(73) Assignee: **Guangdong Jimi Youpin Intelligent Technology Co., Ltd.**, Guangdong Province (CN)

(**) Term: **15 Years**

(21) Appl. No.: **29/853,127**

(22) Filed: **Sep. 13, 2022**

(30) **Foreign Application Priority Data**

Jul. 28, 2022 (CN) 202230486736.X

(57) **CLAIM**

The ornamental design for a combination mug and base, as shown and described.

DESCRIPTION

FIG. 1 is a front elevation view of the combination mug and base, embodying my new design;

FIG. 2 is a left side elevation view thereof;

FIG. 3 is a right side elevation view thereof;

FIG. 4 is a rear elevation view thereof;

FIG. 5 is top plan view thereof;

FIG. 6 is a bottom plan view thereof;

FIG. 7 is a top, front and right side perspective view thereof, and,

FIG. 8 is a bottom, front and right side perspective view thereof.

The broken lines depict portions of the combination mug and base that form no part of the claimed design.

1 Claim, 8 Drawing Sheets
